UNITED STATES PATENT OFFICE.

CHARLES LEWIS CARMAN, OF RIVERSIDE, CALIFORNIA.

FEEDER.

1,069,527.

Specification of Letters Patent.

Patented Aug. 5, 1913.

Application filed June 21, 1912. Serial No. 705,008.

To all whom it may concern:

Be it known that I, CHARLES LEWIS CARMAN, a citizen of the United States, residing at Riverside, in the county of Riverside and 5 State of California, have invented certain new and useful Improvements in Feeders, of which the following is a specification, reference being made to the accompanying drawings.

10 My invention relates to grinding machines in general and more particularly to an improved feeder adapted for use in connection with a tube mill or rotary kiln.

The principal objects of my invention are 15 the provision in a tube mill or the like of an improved feed means by which a uniform feeding operation is attained and flooding of the mill effectually prevented; the provision in a feeder of a series of suitable annular feed compartments so arranged that should one compartment become obstructed and checked by a foreign substance the remaining compartments have continuous rotation independently of the one arrested; 20 and the provision in a feeder of novel means by which the flow of material is readily controlled without necessitating stoppage of the apparatus.

These and such other objects as may here- 30 after appear or are incidental to my invention I attain by means of a construction illustrated in preferred form in the accompanying drawings, wherein:—

Figure 1 is a side elevation in section of a 35 tube mill showing my improved feeder applied thereto.

Figure 2 is a vertical central section through the feeder.

Figure 3 is an end elevation of Figure 2. 40 Figure 4 is a plan view of the compartments.

Figure 5 is a perspective of one of the rings.

Feeders of the class described are com- 45 monly applied to pulverizing machines and particularly to tube mills and rotary kilns. One of the disadvantages of some of the types of feed now in use is the tendency to flush or flood the machine whenever the 50 material in the bin leading to the feeder is partially emptied and the material consequently in motion. This has been fully met and overcome by my novel arrangement of a series of annular rings having frictional 55 contact with a rotary drum, each ring car-

rying a plurality of lugs forming compartments when positioned in contact with other similar rings. Each compartment after being filled is completely inclosed while revolving it until it reaches a point where its 60 contents are discharged, thus obtaining an uniform feed operation and effectually preventing flooding of the mill. These compartments are furthermore independent in their rotation with respect to each other so 65 that in the event of any foreign substance working through from the bin or the conveyer means into one of the compartments the operation of the unaffected compartments is continuous.

70 The novel means adapted to control the flow of the material to the mill is so arranged that the feeding operation is not hindered in any way and stoppage of the feeder for any adjustment of the control is not re- 75 quired.

Referring now more particularly to the preferred construction in the accompanying drawings, I show my invention applied to a tube mill 6 carrying a scoop 7 which is 80 adapted to revolve within a housing 8. An opening 9 is provided in the housing around which opening is mounted a feeder 10 provided with an inlet opening 11 leading to a bin 12 containing pulverized material to be 85 fed to the mill.

As will be seen by referring to Figures 2 and 3 the feeder 10 comprises a frame-work 13 carrying vertical flanges 14 to which is bolted a flanged chute member 15 90 forming a connection between the feeder and the bin. Mounted in the frame-work is a hollow trunnion 16 secured thereto by bolts 17 and provided with a bearing box 18 in which is placed a bushing 19 for the re- 95 ception of a drive shaft 20. Fitting around the trunnion 16 is a bushing 16^a providing a bearing surface for a hub portion 21 of a rotary drum 22, the said hub portion having an inner shoulder 21^a bearing against the 100 end of the trunnion. The drum has rotation freely within the frame-work and carries a flange 23 at one end of its periphery.

Fitting circumferentially around the periphery of the drum and having frictional 105 contact therewith are a series of annular rings 24, each ring, except the first one adjacent the flange 23, being provided on one side with a plurality of lugs 25. When the rings are placed on the drum the free edges 110

26 of the lugs engage the surface 27 of the next ring in such a way as to form a series of compartments 28 for the reception of the material from the bin. These rings when 5 positioned on the drum fit closely together and are held in place by the annular flange 23 and a keeper ring 29. The surfaces of the outer rings are flush with the walls of opening 11, eliminating any possibility of 10 leakage of the material.

10 The shaft 20 is preferably driven from the mill by any suitable means, so that when the tube mill revolves rotation is imparted to the shaft. The other end of the shaft 15 within the feeder is cored and slotted for the reception of a clutch rod 31 and key 32 having reciprocal movement therein, the key 32 on movement of the rod in one direction engaging with a key-way (not shown) in the interior face 33 of the hub 21. Mounted on the shaft and secured thereto by set screws 34 are collars 35 and 36 bearing against the trunnion 16 and the hub 21 respectively. Resting upon the upper 20 frame-work and having movement in 25 grooves 37 formed by the vertical flanges 14 and chute member 15 is a plate 38 provided with a lip 39 adapted to cut off one or more of the series of compartments as desired, in 30 this way the quantity of material to be fed to the mill is under complete control.

35 The operation of the apparatus is substantially as follows: The clutch rod and key having been moved outwardly to engage with the key-way in the hub of the drum, rotation is then imparted to the shaft. When one horizontal row of the compartments is filled by the material from the bin, it moves past the feed opening and its place 40 is taken by the next horizontal row of compartments. The filled compartments are inclosed by the frame-work 13 from the time it is filled until it reaches a point substantially where it discharges into the housing 8, thereby preventing any leakage of the material and obtaining an uniform feeding 45 operation while any material remains in the bin. This will readily be seen by a reference to Figure 3.

50 When it is desired to vary the flow of the material the cut-off plate is moved over to cut off one or as many as desired of the series of annular compartments from the material in the chute, the lip 39 engaging with 55 the rings. When the feeder is to be stopped the clutch rod is moved inwardly disengaging the drive shaft from the rotary drum.

60 In the event of any foreign substance working through from the conveyer or from the bin and obstructing one of the compartments, the movement of that annular ring forming such compartment will be arrested, until such time as the foreign substance is 65 removed. When one ring is checked, the rotation of the remaining rings is continuous

and uninterrupted. Other advantages will occur to those familiar with the art.

Having thus described my invention and illustrated its use what I claim as new and desire to obtain by Letters Patent is the 70 following:

1. In a feeder the combination of a frame provided with a feed passage, a rotary drum mounted for movement within the frame, a drive shaft, connections between the drive 75 shaft and the rotary drum, and a ring having frictional contact with the periphery of the drum and provided with a plurality of lugs forming compartments substantially as described.

2. In a feeder the combination of a framework, a trunnion mounted in the framework, a rotary drum fitting over the trunnion, a shaft through the trunnion, means to connect the shaft to the rotary drum, and 80 an annular ring having frictional contact with the drum and provided with a series of lugs forming compartments and adapted to rotate with the rotary drum substantially as described.

3. In a feeder for a tube mill or the like, the combination of an inclosing frame having a feed inlet and a discharge outlet therein, a rotary drum mounted for movement within the frame, driving means, a connection between the driving means and the rotary drum, and a plurality of annular rings each provided with a lug adapted to contact with adjacent rings to form compartments, 90 said compartments being entirely inclosed 95 by the frame at all points between the feed inlet and the discharge outlet.

4. The combination in an apparatus of the class described of a frame provided with a feed opening and a discharge opening therein, a trunnion mounted in the frame-work, a rotary drum fitting over the trunnion, a drive shaft, a connection between the drive shaft and the drum, and a plurality of rings removably fitting on the drum and provided with lugs adapted to contact with adjacent rings to form compartments, so that on stoppage of one row of compartments under abnormal conditions another row of compartments has uninterrupted 100 rotary movement, substantially as described.

5. The combination in a feeder, of a housing having a feed opening and a discharge opening therein, a rotary drum mounted for movement in the housing, a drive shaft, connections between the shaft and the said drum, a series of movable compartments mounted on the drum and frictionally movable therewith comprising a plurality of annular rings provided with lugs, each ring 110 spaced away from the adjacent ring by the said lugs.

6. In a feed device of the character described, the combination of a feed conduit, a rotary feed member therein, and a shaft for 115

turning said feed member and having frictional engagement therewith, the rotary feed member comprising a plurality of sections placed end to end on the shaft.

5 7. In a feed device of the character described, the combination of a feed conduit, a rotary feed member therein, and a shaft for turning the feed member, the said feed member comprising a plurality of sections 10 having frictional engagement with the shaft and provided with laterally projecting members whereby the sections when placed end to end form radial compartments in the feeding member.

15 8. In a feed device of the character described, the combination of a feed conduit, a drum mounted for rotation in said passage, means for rotating the drum, and a plurality of propelling members mounted

on the drum and having frictional engagement with the drum. 20

9. In a feed device of the character described, the combination of a feed conduit, and a rotary feed member mounted therein, consisting of a plurality of substantially 25 similar and independent sections provided with laterally projecting members in frictional contact with an adjacent section, whereby the sections when placed end to end form radial compartments. 30

In testimony whereof, I have hereunto signed my name in the presence of the two subscribed witnesses.

CHARLES LEWIS CARMAN.
